LIGHTING FIXTURE WITH LAMP-REMOVAL BAFFLING

Arthur L. Rosenstein, Chicago, Ill., assignor to Luminous Ceilings, Inc., Chicago, Ill., a corporation of Illinois

Application May 15, 1958, Serial No. 735,415

3 Claims. (Cl. 240—51.11)

This invention has as its principal object the provision of improved baffle means for use in lighting fixtures such as troffers and particularly characterized in that the lighting fixture includes a trough-like reflector means housing elongated fluorescent tubes, and the baffle means is positioned internally of the trough at spaced positions along the length thereof, the baffle being shiftable in a certain manner into positions of alignment lengthwise of the fluorescent tubes in order that the latter may be inserted and withdrawn readily from the trough fixture, especially by means of a lamp changer's pole.

A more particular object of the invention is the provision of a trough-like lighting fixture for elongated lamps, and a plurality of baffles mounted to pivot, and linked together to pivot into positions of alignment lengthwise of the fixture.

Additional aspects of novelty and utility relate to details of the construction and operation of the illustrative embodiment of the invention as described hereinafter in view of the annexed drawing, in which:

Fig. 1 is a perspective view of a lighting fixture equipped with the novel baffle means;

Fig. 2 is a plan view looking up into the bottom of the device of Fig. 1;

Fig. 3 is an enlarged cross-section looking in the direction of lines 3—3 of Fig. 2;

Fig. 4 is a fragmentary sectional detail looking in the direction of lines 4—4 of Fig. 3;

Fig. 5 is a sectional detail taken along lines 5—5 of Fig. 3.

The drawing in Fig. 1 shows a type of lighting fixture sometimes known in the trade as a "Trougher" or "Troffer," such devices being characterized broadly by the fact that they are commonly elongated and comparable in shape to an inverted trough.

The fixture shown in Fig. 1, for example, includes a pair of elongated side walls 10 and 11, a pair of end walls 12 and 13, and a top 14, seen to better advantage in Fig. 3.

Situated at spaced points along the interior of the trough are baffles 21, 22, and 23, mounted for joint pivotal movement in a manner to be described.

Above the baffles are elongated tubular fluorescent lamps 8 removably supported by sockets 9 (Figs. 2 and 3) located at opposite ends thereof and of a character well known in the art such that lamps may be seated therein, or removed therefrom by certain simple inserting and turning motions which may be effected by an attendant using a common lamp pole P, the general form of which is indicated in Fig. 1, such poles having a yoke-shaped clamp C at the end thereof, the jaws of which may or may not be mechanically operable by a hand-lever mechanism (not shown) extending to the lower end of the pole.

Such lamp poles are of varying degrees of refinement and are in common use to enable an attendant to change lamps in overhead fixtures without use of a ladder.

According to the construction particularly evident in

2

Figs. 3 and 5, each of the light baffles fits closely, but with some marginal swinging clearance, into the trough and is normally disposed transversely of the latter for baffle operation, as in Fig. 1.

5 Each baffle is pivotally mounted centrally along its upper margin as by means of pivot bolts 27 extending through suitable apertures on the offset upper edge flange 21X provided on each baffle plate.

The pivots 27 are seated in the bottom wall 30 of channel member which serves as a multiple reflector and compartment partition, and also as a baffle mounting, this member having a pair of upwardly pitched reflectory faces or walls 31, 32, and respectively continuing in opposite lateral offsets 31A, 32A, which are each joined to one of the trough side walls, as at 31X, by spot welding or the like. Pivot bolts 27 are preferably equipped with friction means, such as springs 28, tensionable by nuts 29 sufficiently to maintain the individual baffles in any position of adjustment.

10 The several baffles are linked for joint pivotal motion by means, such as depicted in Fig. 2, comprising a first rigid link arm 34 pivotally attached as at 35, 36 to, and interconnecting, the baffles 21 and 22 at one side of a common center line through all pivots 27; and a second rigid link arm 38 similarly interconnecting baffles 22 and 23 as at 37, 39, but on the opposite side of said common center line.

15 The link arms 34 and 38 are simple angle bars attached as in Fig. 4 by free pivot rivets or bolts, which are set through the aforesaid offset upper edges (21X) of the respective baffles.

20 Thus, an easy turning movement applied to any baffle will turn all in unison, and when it is desired to service or remove any of the fluorescent lamps 8, a lamp-pulling tool such as the pole P serves well to apply the necessary force to swing all baffles simultaneously into substantially longitudinal alignment, as indicated by the dotted-line positions depicted in Figs. 2 and 3.

25 Long troughers with a larger number of jointly swinging baffles are entirely feasible, although it is generally desirable to limit the length of these units to the length of the longest fluorescent tubes available.

I claim:

30 1. In a trougher for elongated lamps, a plurality of baffle plates centrally pivoted at spaced points along the inside length of the trougher to pivot about an axis at right angles to the top of the trougher from normal position respectively transverse to the trougher and lamps into positions approximately in line with a median lengthwise axis through the trougher and means linking said baffles for joint pivotal motion, as aforesaid, whereby the baffles may be moved into non-obstructing position to facilitate entry and removal of said lamps from the trougher.

35 2. In a lighting fixture for elongated tubular lamps including a trough in which the lamps are seated, baffle means mounted pivotally in the trough at points along a median line such that said baffles can be turned into a normal position each disposed in a plane substantially parallel to the plane of the other and transverse to said trough and said lamps and median line; and means linking said baffles for joint pivotal motion from said normal position into positions in which each baffle is turned into a plane nearly parallel with said median line and the lengthwise axis of said lamps so as to lie in non-obstructing relation to the lamps to permit removal of the latter from the fixture.

40 3. A lighting fixture in the form of an elongated housing having a top portion and side wall portions depending therefrom, at least two elongated lamps disposed in said housing lengthwise thereof one on each side of a median line extending lengthwise of said housing; socket

45 4. A lighting fixture having a top portion and side wall portions depending therefrom, at least two elongated lamps disposed in said housing lengthwise thereof one on each side of a median line extending lengthwise of said housing; socket

means removably mounting the lamps in the housing as aforesaid; means attached to the housing and providing at intervals along said median line a pivotal support for a baffle; a baffle plate carried by each said pivotal support for movement into and out of baffling positions in which the baffles are in plane approximately parallel to each other and transverse to said lamps and obstructing removal of the lamps outwardly of the fixture; to non-obstructing positions in which the several baffles are turned into longitudinal positions each in a plane substantially parallel to the other and the length of said

lamps; and means pivotally inter-connecting all baffles to pivot the same into said non-obstructing position responsive to a turning moment applied to any baffle.
